Primary Examiner—Cathron C Brooks*Assistant Examiner*—Karen E Kearney(74) *Attorney, Agent, or Firm*—Hamilton, Brook, Smith & Reynolds, P.C.(57) **CLAIM**

The ornamental design for a computer generated graphic icon for computer screen, as shown and described.

DESCRIPTION

The FIGURE is a front view of a computer generated graphic icon for computer screen showing our new design. The broken line showing of the computer screen is for the purpose of illustrating environmental structure and forms no part of the claimed design.
